UNITED STATES PATENT OFFICE.

PETER GUSTAF LEONARD, OF WEST TULSA, OKLAHOMA.

TUBING CATCHER.

Application filed April 4, 1927. Serial No. 180,666.

My invention relates to a tubing catcher, and more particularly to catcher or anchor means used in conjunction with oil tubing, for the purpose of anchoring and holding said tubing in the oil well casing upon any sudden rupture or drop of said tubing in the well casing.

The main object of my present invention is to provide a tubing catcher for automatically and unfailingly anchoring the tubing in the well casing upon sudden drop of said tubing; and moreover to provide the device with means and arrange the entire construction so that the catching means can be also automatically released by a forceful or sudden pull on the tubing, and the tubing can then be easily either raised from or again lowered in the well casing. Another object is to provide the catching or gripping means in the shape of preliminary gripping means and main gripping means, carried by said preliminary gripping means, and becoming effective upon the actual gripping and stopping of the latter. A further object is to provide means for automatically and positively releasing both the preliminary and the main gripping means by a forceful pull on the tubing. Still another object is to provide means for safely retaining both sets of gripping means normally in their released position, and including means for guiding the main gripping means and preventing undue or injurious outward movement or swinging thereof.

These and other objects and advantageous ends are attained with my invention, as will become apparent from the following description, taken in connection with the accompanying drawings, in which,

Fig. 1 is an elevational view of my improved tubing catcher, shown in its release position in a well casing;

Fig. 2 is a vertical sectional view thereof, taken along line 2—2 on Fig. 4, and showing the device in the gripping or operative position;

Fig. 3 is a sectional view similar to Fig. 2, but taken along line 3—3 on Fig. 4;

Figs. 4, 5, and 6 are horizontal cross-sectional views, taken respectively on lines 4—4, 5—5, and 6—6 on Fig. 2; and

Fig. 7 is a horizontal cross-sectional view, taken on line 7—7 on Fig. 1.

In the drawings I have illustrated my invention in its preferred form of construction, which comprises a tubing section or

tube 10, forming a central member for supporting the other elements, and being adapted to be used in place of an ordinary tubing section. Guide members 11, provided with guide arms 12, are threaded on the ends of tube 10, and may be utilized as coupling members, as indicated in the drawings.

The gripping means or mechanism in this form of my invention comprises two sets of gripping means, preliminary gripping means and main gripping means. The preliminary gripping means preferably includes a pair of gripping elements 13 positioned at opposite sides of the central member or tube 10, and mounted on resilient arms or strips 14 which are fastened on a supporting member or sleeve 15 movable longitudinally on tube 10; said elements being placed in notches 16 in said sleeve and movable transversely therein against the inner wall of a well casing 17. The main gripping means preferably includes a plurality of elongated gripping elements or gripper slips 18 which are pivotally supported in pairs on the preliminary gripping elements 13, as by means of a yoke or curved rod 19 pivoted with its intermediate portion or yoke in an element 13 and carrying pivotally on its two ends 19' a pair of these elements 18. Suitable gripping teeth are provided on the outward edges of these elements 13 and 18 to bite or grip firmly the well casing 17, as indicated in Figs. 2, 3 and 4 of the drawings.

The means or mechanism for moving the gripping elements 13 and 18 into operative or gripping position comprises a spreading member in the form of a tapering collar 20 mounted on the central tube 10, and positioned to engage the inward edges of elements 13 and spread or force these elements into their operative or gripping position. This collar 20 is normally seated and held on an enlarged portion or shoulder 21, surrounding tube 10, by the action of an imprisoned spring 22 which surrounds the tube between said collar and the upper guide member 11. This spring and arrangement adapts the device for use in various sized casings, since the spring functions to let the tubing sink further down through the collar, when the device is operating in a larger casing, and between the times or moments that the elements 13 have been moved into gripping position and that the elements 18 are moved into their gripping position. These main gripping elements 18 are spread

or moved into their gripping or operative position, by means of a tapered or conical spreading member 23 which is freely movable on tube 10, and is resiliently supported by a spring 24 positioned between said member 23 and the lower guide member 11. This spring normally supports member 23 and thereby also sleeve 15 and the gripping elements 13 and 18, as best indicated in Fig. 1, and allows the upward movement of tube 10 through the same during the release stroke or releasing of the device, by the sudden upward pull on the tubing.

The means for positively and automatically releasing all the gripping elements, of both sets of gripping means, comprises a releasing member or collar 25 which is positioned on tube 10 adjacent the lower guide member 11. Upon an upward stroke or forcible pull on the tubing, this collar serves the purpose of breaking loose the conical member 23 from gripping elements 18 and forcing said member upwards along said elements. In the mean time the shoulder 21 on tube 10 has been effective in releasing and lifting the tapered collar 20 up and free from elements 13. Thus both sets of elements are positively released by an upward stroke of the tubing.

Further means is provided, in the form of guiding means, for aiding said releasing means, and to guide the main gripping elements 18 into their release position and also into their operative position and to prevent excessive or undue outward movement thereof. This means comprises guide fingers or pins 26 at the lower ends of elements 18, and lugs or ears 27 at the lower end of conical member 23, having bores or holes 28, to contain and guide said fingers. The meeting faces or surfaces of elements 18 and the lugs are also tapered or curved at a slant to assist the fingers in positively guiding and returning these elements into their original released position. In the mean time the preliminary gripping elements 13 have been returned to their retracted or released position by the resilient arms 14, upon withdrawal of collar 20 by shoulder 21.

50 *Operation of my improved tubing catcher.*

This catcher device is connected to the well tubing and lowered therewith into the well casing, with the parts placed in their release position, as best indicated in Fig. 1 of the drawings; while the gripping elements 13 and 18 are supported with sleeve 15 on conical member 23, which partially depresses spring 24, while tapered collar 20 rests on shoulder 21. Upon any sudden dropping of the string of well tubing, equipped with my catcher device, into the well casing, the spring 24 expands and retards the fall of the movable members and elements supported thereby, namely 23, 15, 14, 13, 19, 18, 26,

and 27; whereupon collar 20, which is descending with tube 10 and urged by spring 22, then wedges elements 13 outward and forces them into positive gripping position, as best shown in Fig. 2. This spring 22 becomes more compressed and permits tube 10 to sink farther through collar 20 when the device is used in a casing of greater diameter, and the gripping elements 13 and 18 must be spread farther apart, than in a smaller casing. In the mean time conical member 23 has been engaged and forced downward by shoulder 21 on tube 10, thereby forcing the main gripping elements 18 outward into positive gripping position, as shown in Figs. 2, 3 and 4; whereupon both sets of gripping elements remain effective in positively and securely holding the string of tubing in a stationary position in the well casing, until the gripping elements are released by my automatic releasing means, releasing collar 25, provided with this improved device.

When it is desired to release this catcher device and to withdraw the tubing from the well casing, it is only necessary to give a sudden or forcible upward pull or stroke on the tubing; in consequence whereof the shoulder 21 on tube 10 will carry collar 20 upward from between the gripping elements 13, and spring arms 14 will then automatically retract and release said elements; while in the mean time spring 24 has become sufficiently compressed to allow the releasing collar 25 to strike the lower end of conical member 23 and positively force said member upward along the retarded gripping elements 18 to release the same; and these elements are then, through the action of fingers 26 assisted by the slantingly curved meeting faces at the ends of elements 18 and lugs 27, furthermore drawn inward and returned into their original release position. The parts are thus returned automatically to their original release position, by an upward stroke on the tubing, and said tubing may thereafter be raised or moved freely in the well casing as desired, and all set for any further accidental dropping of the tubing.

Although this application discloses my invention in its preferred form, it should be understood that various changes in the construction may be resorted to and are intended to be comprehended hereby, as far as warranted by the existing prior art.

What I claim as my invention and desire to secure by Letters Patent is:

1. A tubing catcher comprising preliminary gripping means and main gripping means, all normally carried released from the well casing, and means for automatically moving the gripping means, upon a rapid drop, to grip the casing at any elevation therein.

2. A tubing catcher comprising preliminary

nary gripping means normally held released from the well casing and main gripping means carried thereby, and means for moving said preliminary gripping means into gripping position automatically upon a drop at any elevation in the well casing and thereupon automatically forcing said main gripping means into operative position.

3. A tubing catcher comprising various sets of gripping means, all normally held released from the well casing, means for actuating said sets of gripping means in succession, and means for releasing said actuating means and retracting all sets of gripping means from the casing automatically by a pull on the device.

4. A tubing catcher comprising serrated preliminary and main gripping means, operating means for actuating first the preliminary means and then the main means automatically into gripping position upon a sudden dropping of the device, and means for automatically releasing said actuating means and retracting all gripping means from the well casing by a forcible pull on the device.

5. A tubing catcher comprising preliminary and main gripping means, both normally held released and spaced from the well casing, means for moving said preliminary means and thereupon said main means into gripping position, and means for releasing first said preliminary and thereafter said main gripping means automatically.

35 6. A tubing catcher comprising preliminary gripping means and main gripping means carried thereby, both normally held spaced from the well casing, separate means for actuating said preliminary means and thereupon said main means automatically by a pull on the tubing.

45 7. A tubing catcher comprising a central tube, preliminary and main gripping means mounted to move longitudinally of said tube and spaced from the well casing, means movable longitudinally of said tube to automatically move said preliminary and said main means in succession into gripping position, upon a drop at any elevation in a well casing, and means for automatically bringing said gripping means into their original release position.

8. A tubing catcher comprising a central member, means movable on said member and having gripping means carried by resilient arms thereon to be normally held in release position, a collar for moving said gripping means into gripping position, and fixed means on said member for lifting said collar to release said gripping means automatically by a pull on said member.

65 9. A tubing catcher comprising a central

tube and a member movable thereon, serrated gripping means supported on said member for transverse and longitudinal movement relative to the tube, a collar movable longitudinally on said tube for spreading said means, and a shoulder on said tube for positively moving said collar and releasing said gripping means.

10. A tubing catcher comprising a tube and a sleeve slidable thereon, gripping means mounted with resilient arms on said sleeve for movement transversely thereof and longitudinally therewith, a slidable collar for moving said means to operative position, and means for moving said gripping means against said collar to spread the means.

11. A tubing catcher comprising a tube and a sleeve slidable thereon, gripping means mounted on said sleeve for transverse movement, a member resiliently held and movable on said tube, means for resiliently supporting said sleeve and gripping means and to move the means onto the member for rendering said means operative, and shoulder means on the tube for positively withdrawing said member to release said gripping means.

12. A tubing catcher comprising a tube and a member movable thereon, gripping elements movably carried by said member, tapered means for spreading said elements, other gripping elements pivotally carried by the first elements, a member supporting said first member and said elements thereby, and a spring normally depressed by said supporting member but becoming operative to move said members and said elements to spread the first elements by said tapered means and the other elements by said supporting member, upon a sudden dropping of the tube.

13. A tubing catcher comprising a tube and a member movable longitudinally thereon, gripping elements carried by said member to remain normally in released position, means for spreading said elements, second gripping elements carried by the first elements, a member normally supporting the first member and thereby all the gripping elements also being adapted to operate said second elements, a spring resiliently supporting said members and elements, and members spaced apart on the tube for engaging said spreading means and said supporting member to positively release all the elements by an upward stroke of the tube.

14. A tubing catcher comprising a tube and a conical member movable thereon, means with gripping elements thereon adapted to be supported by said member, gripper slips connected to said elements, means to force said member loose from said slips and to release said slips and elements, and means to guide said slips into their release position.

15. A tubing catcher comprising a tube

- and a conical member movable thereon, means movable to be supported by said member and carrying gripping elements thereon, gripper slips carried by said elements, separate means on the tube for releasing said elements and slips, and guide means on said slips and said member for guiding said slips into their original release position.
16. A tubing catcher comprising a tube, a member movable thereon and having gripping elements mounted to be normally moved to release position, means for moving said elements into gripping position, a shoulder on the tube for moving said means to release said elements, gripper slips connected to said elements, a spreading member to operate said slips, and means to knock said spreading member loose from said slips.
17. A tubing catcher comprising a tube, a sleeve with gripping elements resiliently carried thereby, a collar for actuating said elements, gripper slips pivotally carried by said elements, a member for operating said slips and being adapted to normally support said sleeve and elements and slips in their release position, and means on the tube, including a shoulder to lift said collar also means to force loose the member from the slips, for positively releasing the gripping elements and slips by an upward stroke of the tube, and to return them to their original release position.
18. A tubing catcher comprising a tube, a sleeve and gripping elements mounted with resilient arms thereon to retract said elements, a collar for spreading said elements, gripper slips mounted with yoke means pivotally on said elements, a spring permitting said collar to adjust itself on the tube while spreading said elements, a conical member for spreading said slips, means to guide the slips into release position, means on the tube to positively lift said collar and release said elements by a pull on the tube, a spring supporting said member and elements and slips which expands to actuate them into operative position, and a collar

fixed on the tube to force said member loose from said slips after compressing said spring, by an upward pull on said tube.

19. A tubing catcher comprising a central tube, gripping elements and means for swingably supporting them, an operating member slideable on said tube for moving said elements into gripping position, a spring on said tube to normally support said member in release position relative to said elements, and means secured on said tube to stress said spring and engage and knock loose said member from said elements, upon a forcible pull on said tube, for positively releasing said elements.

20. A tubing catcher comprising a central tube, gripping elements and means for pivotally supporting them, a conical member for spreading said elements, a coil spring surrounding said tube and normally supporting said member in release position relative to said elements, and means including a releasing collar secured on said tube to compress said spring and then engage under said member and positively knock it loose from said elements to release them from their gripping position, upon a forcible pull on said tube.

21. A tubing catcher comprising a central tube, gripping elements movable transversely thereof, an operating member for moving said elements into gripping position, a spring on said tube to normally support said member and to be slightly compressed when said member holds said elements in gripping position, guide means secured to said tube and supporting said spring, and a releasing member secured to said tube above said guide means to engage said operating member and positively knock it loose from said elements while said spring has been further compressed by said guide means, for releasing said elements from their gripping position.

In testimony whereof I have signed my name to this specification.

PETER GUSTAF LEONARD.
